UNITED STATES PATENT OFFICE.

JACQUES GREENBERGER, OF NEW YORK, N. Y.

SURGICAL INSTRUMENT.

1,285,131.

Specification of Letters Patent.

Patented Nov. 19, 1918.

Application filed March 6, 1917. Serial No. 152,564.

To all whom it may concern:

Be it known that I, JACQUES GREENBERGER, a citizen of the United States, residing in the borough of Manhattan, city, county, and State of New York, have invented a certain new and useful Surgical Instrument, of which the following is a specification.

My invention relates to surgical instruments, and is adapted more particularly to an instrument for performing operations for removal of the tonsils, the soft palate or other minute and readily accessible organs, or growths, such as adenoids and the like.

15 The objects of my invention are minor operations to be performed in such a manner that a minimum of hemorrhage will occur, and by means of which such hemorrhage as does occur will take place after the 20 organs have been removed and the operation completed.

A further object is to provide means for placing the instrument in position, and securing it to the part of the organ to be amputated before the cutting operation is commenced.

Another object is to provide means to facilitate the removal of the organs desired to be amputated, with a minimum expenditure 30 of energy on the part of the operating physician, and minimizing the pain of the patient by enabling the operation to be performed with greater skill and despatch than now practised.

35 Another object is to provide means for the ready removal of the severed organs.

These and further objects will more fully appear in the following specification and accompanying drawings considered together 40 or separately.

I have illustrated one embodiment of my invention in the accompanying drawings, in which like parts are designated by similar reference characters, and in which,

45 Figure 1 is a top plan view of an instrument embodying my invention;

Fig. 2 is a side elevation partly in central longitudinal section;

Fig. 3 is a section on the line 3—3 of Fig. 1;

Fig. 4 is a section on the line 4—4 of Fig. 1;

Fig. 5 is a section on the line 5—5 of Fig. 2;

Fig. 6 is a section on the line 6—6 of Fig. 2;

Fig. 7 is a section on the line 7—7 of Fig. 2; and

Fig. 8 is a detail sectional view of the slide accommodating a snare portion of the 60 apparatus.

In carrying out my invention, I employ a tonsilectome which has been modified to form a base or clamp for carrying a snare. A snare may be detachably mounted on the 65 clamp and movable relatively therewith; the said snare performing the cutting operation when desired.

In the drawings, A designates the modified snare, and B the base or clamp formed 70 of a modified tonsilectome. The base or clamp comprises a handle 1 by means of which it may be supported in position. The handle carries a base plate 2, the outer extremity 3 of which is of a spatula form with 75 a U shaped rim 4, provided on the inner surface with a groove or recess 5; the said spatula having an opening 6 therein.

A slide 7 is mounted on the face of the base plate and is movable relatively thereto. 80 The slide is guided by studs on the base working in slots in the slide, and is held in contact with the base by means of a spring member 8 carried by one of the studs. The front end 8^a of the slide is flattened to 85 tongue shape, and its forward edge is so rounded and shaped so as not to come into contact with the recess 5 at the front of the spatula, but is so adjusted and limited in movement by the action of the spring member 8 as to prevent cutting the tonsil or other 90 organ, but have a sufficient forward movement to securely hold in position the organ upon which the operation is to be performed. The recess 5 acts as a receptacle 95 for the wire 16 when it is desired to adjust the same preparatory to performing the cutting operation. The rear end of the slide is provided with gripping means having an opening 100 therein, by means of which it may be moved relatively to the base plate.

Secured to the base plate is a U shaped guide 9, the sides of which extend above the slide 7. The inner portion of each side of the guide is provided with a groove 10, 105 being inclined relatively to the slide 7. The rear end of each side of the guide is provided with an inclined face 11 and a notch 12.

The snare A comprises a tube 13 within 110 the bore of which a rod 14 is freely movable, as hereinafter described. The rear end

of the rod is provided with a screw threaded portion 15, and its forward, reduced extremity is provided with the usual means for attaching the wire loop 16, by means of which the cutting is accomplished. The rear portion of the tube 13 is slotted for a considerable portion of its length on diametrically opposite sides, as at 17, and finger pieces 17^a are secured to the rod 14 and project through the slots, and prevent rotation of the rod. The forward end of the tube is flared, as at 18, and is provided with teeth or prongs 19.

The tube 13 is provided with trunnions 15, 20, which are adapted to engage the grooves 10 of the guide 9.

A spring 21 carried by the stud 22 of the base plate engages the under side of the tube 13, and holds the snare in proper angular relation to the base plate.

A nut 23 engages the threaded portion of the rod, and a thumb piece 24 is provided at the rear end of the tube 13, the said thumb piece having a threaded portion so as to permit its removal for the purpose of enabling the removal of the tube 13 for cleaning or otherwise.

The operation is as follows: The slide 7 is moved to the rear until the opening 6 is disclosed. The snare A with the loop 16 attached to the end of the rod 14 which projects a short distance from the forward end of the tube 13, is placed in position between the sides of the guide 9 with the trunnions 20 resting in the notches 12, and in line with the grooves 10. The spring 21 will retain the tube in position. The loop 16, by its own flexibility, is distended, and its forward end rests within the recess 5.

The instrument is then placed in position with a tonsil, for example, projecting through the opening 6. The slide 7 is now pushed forward and presses the neck of the tonsil against the base of the U shaped rim 4.

The thumb piece 24 is pushed forward, which moves the tube 13 so as to draw the end of the rod into the tube, closing the loop of the wire 16, and withdrawing it from the recess 5, and engages the neck of the tonsil between the wire and the end of the tongue 8.

The tube is pushed forward until that portion of the tonsil which is to be removed, is impaled upon the teeth or prongs 19 on the end of the tube. When the tube has reached this position, the trunnions 20 have traversed the entire length of the grooves 10, and the base or clamp B is automatically released from the snare A, leaving it attached to the tonsil and in proper position to sever the same. No blood has been shed, and the entire operation has been plainly visible to the operator, and has been per-

formed without discomfort or pain to the patient.

If it is desired to remove the other tonsil, the snare A is held in position by suitable means, or by an assistant. A new snare A 70 is placed in position on the base or clamp, and the above described operation is repeated.

When both tonsils are securely held in the snares, the nut 23 is wound up on the threads 17, the rod is withdrawn farther into the tube, drawing the loop 16 entirely within the tube, and severing the tonsil which will remain impaled on the end of the tube by the prongs 19, so that there will be no danger of its dropping into the throat of the patient. The operation just described is performed with the utmost despatch, greater than now in practice, and with a corresponding benefit to the patient.

When an assistant is present, the two tonsils may be removed simultaneously.

While I have illustrated the teeth or prongs 19 as an integral part of the tube, they may be so constructed as to be independent thereof, and be so arranged as to be movable relative to the tube, so that the prongs will not protrude from the end of the tube unless and until desired for use in the operation.

In accordance with the provisions of the patent statute, I have described the principle of my invention together with the apparatus which I now consider to represent the best embodiment thereof, but I desire it understood that my invention is not confined to the particular form of apparatus herein shown and described, and, therefore, I claim broadly the right to employ all equivalent instrumentalities coming within the scope of the claims, and by means of which objects of my invention are attained, and the new results accomplished, as herein set forth, as it is obvious that the particular embodiment herein shown and described is only one of many that can be employed to attain these objects and accomplish these results.

Having now described my invention, what I claim and desire to secure by Letters Patent is:

1. In an article of the class described, the combination with a base, of a snare removably secured to the base, and means for releasing the base from the snare.
2. In an article of the class described, the combination with a base, of a snare removably secured to the base, and means for automatically releasing the base from the snare.
3. In an article of the class described, the combination with a base, of a snare removably secured to the base, and means for releasing the base from the snare, and means

for relative adjustment of the base and snare.

4. In an article of the class described, the combination with a base, of a snare removably secured to the base, and means for automatically releasing the base from the snare, and means for relative adjustment of the base and the snare.

5. An article of the class described, having a base, a slide carried by the base, said base having an opening therein, a guide carried by the base, an element carried in the guide and movable relatively to the base, a loop carried by the element, said loop surrounding the opening, means for contracting the size of the loop, and means for automatically releasing the element from the guide.

6. An article of the class described, having a base, a slide carried by the base, said base having an opening therein, a guide carried by the base, an element carried in the guide and movable relatively to the base, trunnions on the element, there being grooves in the guide for engagement of the trunnions, a loop carried by the element, said loop surrounding the opening, means for contracting the size of the loop, and means for automatically releasing the element from the guide.

7. An article of the class described, having a base, a slide carried by the base, said base having an opening therein, a guide carried by the base, an element carried in the guide and movable relatively to the base, a spring carried by the base and engaging the element, a loop carried by the element, said loop surrounding the opening, means for contracting the size of the loop, and means for automatically releasing the element from the guide.

8. An article of the class described, hav-

ing a base, a slide carried by the base, said base having an opening therein, a guide carried by the base, an element carried in the guide and movable relatively to the base, a spring carried by the base and engaging the element, trunnions on the element, there being grooves in the guide for engagement of the trunnions, a loop carried by the element, said loop surrounding the opening, means for contracting the size of the loop, and means for automatically releasing the element from the guide.

9. An article of the class described, having a base, a slide carried by the base, said base having an opening therein, a guide carried by the base, an element carried in the guide and movable relatively to the base, a loop carried by the element and resting in a recess in the base, said loop surrounding the opening, means for contracting the size of the loop, and means for automatically releasing the element from the guide.

10. An article of the class described, having a tube, a needle movable in the base of the tube, a cutting loop carried by the needle, means for drawing the loop within the bore of the tube, and teeth carried by the tube in proximity to the loop.

11. An article of the class described, having a base, a tube secured to but movable relatively to the base, a rod movable in the bore of the tube, a cutting loop carried by the rod, means for drawing the loop within the bore of the tube, there being teeth on the tube in proximity to the loop.

This specification signed and witnessed this 21st day of February, 1917.

JACQUES GREENBERGER.
